[57] ABSTRACT

An input/output controller maintenance arrangement for a communication switching system having a central processor with a main memory therefor and hav-

ing a peripheral adapter unit for transferring information to and from an input/out peripheral device with a device buffer for transferring information between the peripheral adapter and the main memory, includes a plurality of input/output device error detecting units for sensing malfunctions occurring in the input/output peripheral device, a plurality of device buffer error detecting units for sensing malfunctions occurring in the device buffer, a plurality of bi-stable devices for generating error signals in response to the error detecting units sensing malfunctions, an error bi-stable device responsive to the other bi-stable devices generating their error signals for requesting the services of the central processor for maintenance purposes, and control apparatus responsive to the error bi-stable device for monitoring the buffer bi-stable devices to determine whether the malfunction occurred in the device buffer and for monitoring subsequently the adapter bi-stable devices if the malfunction did not occur in the device buffer to determine the source of the malfunction. The input/output peripheral device is a magnetic tape unit in the disclosed form of the invention, and in the case of a malfunction, such as a breaking of the tape, the source of the error is detected quickly and accurately in accordance with the arrangement of the present invention.

INPUT/OUTPUT CONTROLLER MAINTENANCE ARRANGEMENT FOR A COMMUNICATION SWITCHING SYSTEM

BACKGROUND OF THE INVENTION

1. Field of the Invention

This invention relates to an input/output controller maintenance arrangement for a communication switching system, and it more particularly relates to a maintenance arrangement for quickly and accurately responding to malfunctions occurring in input/output devices, such as magnetic tape units, and their controllers, such as device buffers and peripheral adapters.

2. Summary of the Prior Art

Communication switching systems, such as electronic telephone systems, have employed error detecting units for sensing malfunctions occurring in the various different circuits. The error detecting units are scanned by a common control unit to determine when a malfunction has occurred. Such systems have included stored-program central processors for diagnosing the malfunction conditions so that repairs or replacements can be made. However, while such an arrangement may be satisfactory for some applications, the scanning of large numbers of error detecting units can require unduly and unnecessarily long intervals of time for some applications. For example, in an input/output peripheral device, such as a magnetic tape unit, has been used for storing ticketing information, and the accurate storing of such information is extremely important since it is used for billing subscribers to the system. Therefore, any malfunctions, such as the breaking of the tape, must be detected and acknowledged quickly and efficiently as possible. Therefore, it would be highly desirable to have a maintenance arrangement which would quickly detect the presence of malfunctions occurring in an input/output peripheral device and also its controller, such as a peripheral adapter and a device buffer associated therewith.

SUMMARY OF THE INVENTION

Therefore, the principal object of the present invention is to provide a new and improved maintenance arrangement for detecting and acknowledging malfunctions occurring in input/output peripheral devices and their controllers. Another object of the present invention is to provide such a maintenance arrangement, which detects and acknowledges malfunctions occurring in an input/output peripheral device and its controller, and isolates the source of the malfunction in a fast and efficient manner.

CROSS-REFERENCES TO RELATED APPLICATIONS AND PATENTS

The preferred embodiment of the invention is incorporated in a **COMMUNICATION SWITCHING SYSTEM WITH MARKER, REGISTER AND OTHER SUBSYSTEMS COORDINATED BY A STORED PROGRAM CENTRAL PROCESSOR**, U.S. patent application Ser. No. 342,323, filed Mar. 19, 1973, now U.S. Pat. No. 3,835,260 issued Sept. 10, 1974 hereinafter referred to as the **SYSTEM** application. The system may also be referred to as No. 1 EAX or simply EAX.

The memory access, and the priority and interrupt circuits for the register-sender subsystem are covered by U.S. Pat. No. 3,729,715 issued Apr. 24, 1973 by C. K. Buedel for a **MEMORY ACCESS APPARATUS**

2
PROVIDING CYCLIC SEQUENTIAL ACCESS BY A REGISTER SUBSYSTEM AND RANDOM ACCESS BY A MAIN PROCESSOR IN A COMMUNICATION SWITCHING SYSTEM, hereinafter referred to as the **REGISTER-SENDER MEMORY CONTROL** patent.

5 The register-sender subsystem is described in U.S. Pat. No. 3,737,873 issued June 5, 1973 by S. E. Puccini for **DATA PROCESSOR WITH CYCLIC SEQUENTIAL ACCESS TO MULTIPLEXED LOGIC AND**
10 **MEMORY**, hereinafter referred to as the **REGISTER-SENDER** patent.

The marker for the system is disclosed in the U.S. Pat. No. 3,681,537, issued Aug. 1, 1972 by J. W. Eddy, H. G. Fitch, W. F. Mui and A. M. Valente for a

15 **MARKER FOR COMMUNICATION SWITCHING SYSTEM**, and U.S. Pat. No. 3,678,208, issued July 18, 1972 by J. W. Eddy for a **MARKER PATH FINDING ARRANGEMENT INCLUDING IMMEDIATE RING**; and also in U.S. patent applications Ser. No. 281,586
20 filed Aug. 17, 1972 now U.S. Pat. No. 3,806,659 issued Apr. 23, 1974 by J. W. Eddy for an **INTERLOCK ARRANGEMENT FOR A COMMUNICATION SWITCHING SYSTEM**, Ser. No. 311,606 filed Dec. 4, 1972 now U.S. Pat. No. 3,830,983 issued Aug. 20, 1974 by J. W. Eddy and S. E. Puccini for a **COMMUNICATION SYSTEM CONTROL TRANSFER ARRANGEMENT**, Ser. No. 303,157 filed Nov. 2, 1972 now U.S. Pat. No. 3,809,822 issued May 7, 1974 by J. W. Eddy and S. E. Puccini for a **COMMUNICATION SWITCHING SYSTEM INTERLOCK ARRANGEMENT**, hereinafter referred to as the **MARKER** patents and applications.

25 The communication register and the marker transceivers are described in U.S. patent application Ser. No. 320,412 filed Jan. 2, 1973 now U.S. Pat. No. 3,814,859 issued June 4, 1974 by J. J. Vrba and C. K. Buedel for a **COMMUNICATION SWITCHING SYSTEM TRANSCEIVER ARRANGEMENT FOR SERIAL TRANSMISSION**, hereinafter referred to as the **COMMUNICATIONS REGISTER** patent application.

30 The executive or operating system of the stored program processor is disclosed in U.S. patent application Ser. No. 347,281 filed Apr. 2, 1973 by C. A. Kalat, E. F. Wodka, A. W. Clay, and P. R. Harrington for **STORED PROGRAM CONTROL IN A COMMUNICATION SWITCHING SYSTEM**, hereinafter referred to as the **EXECUTIVE** patent application.

35 The computer line processor is disclosed in U.S. patent application Ser. No. 347,966 filed Apr. 4, 1973 now U.S. Pat. No. 3,831,151 issued Aug. 20, 1974 by L. V. Jones and P. A. Zelinski for a **SENSE LINE PROCESSOR WITH PRIORITY INTERRUPT ARRANGEMENT FOR DATA PROCESSING SYSTEMS**.

40 Programs for communication between the data processing unit and the register-sender, in addition to the **SYSTEM** application, are disclosed in U.S. patent application Ser. No. 358,753 filed May 9, 1973 now U.S. Pat. No. 3,819,865 issued June 24, 1974 by F. A. Weber et al.

45 The scanner for the local automatic message accounting subsystem is disclosed in patent application Ser. No. 434,743, filed Jan. 18, 1974 by B. F. Gearing, M. R. Winandy, G. Grzybowski and D. F. Gaon; and in two articles in the **GTE Automatic Electric Technical Journal**, Vol. 13, No. 4 (October, 1972) at pages 177-184 and pages 185-196.

The magnetic tape unit of the local automatic message accounting subsystem is disclosed in patent application Ser. No. 434,742, filed Jan. 18, 1974 by B. F. Gearing et al.

DESCRIPTION OF THE DRAWINGS

FIG. 1 is a symbolic functional block diagram of a magnetic tape unit with its related controller showing its interconnection with the central computer processor and its main memory, the arrangement incorporating the principles of the present invention; and

FIGS. 2-1 through 2-11 are flow charts of a software program module F-74 serving as the magnetic tape handler for the arrangement of FIG. 1.

DESCRIPTION OF THE PREFERRED EMBODIMENT

Referring now to FIG. 1 of the drawings, there is shown a portion of a communication switching system which incorporates the principles of the present invention. The details of the system, which in the preferred form of the present invention is an electronic telephone switching system, are found in the foregoing-mentioned patents, patent applications and articles. The system of the present invention includes a computer central processor CCP for controlling the operation of the system and for facilitating the maintenance thereof, a computer main memory which is a core memory in the preferred form of the present invention, a computer line processor CLP for controlling the gating of interrupt signals to the computer central processor CCP for interrupting its operation and servicing the requests, which may either be call processing requests for the telephone system or maintenance requests, and a magnetic tape unit including a magnetic tape transport 10, a magnetic tape electronic unit MTE for controlling the unit 10, a magnetic tape peripheral adapter MPA for transferring information to and from the tape transport 10, and a ticketing device buffer TDB for transferring information between the magnetic tape peripheral adapter MPA and the computer central processor CCP and its memory CMM via the computer line processor CLP. The magnetic tape peripheral adapter MPA and the ticketing device buffer TDB comprise the controller for the tape transport 10. The tape transport 10 includes a magnetic tape 12 for moving in the direction of the arrow from a supply reel 14 past an erase head 16, a write head 18 and a read head 21 to a take-up reel 23. The input/output peripheral device in this case is the magnetic tape transport 10 and its magnetic tape electronic unit MTE.

In order to sense malfunctions occurring in the input/output peripheral device, a plurality of error detecting units are employed to sense the occurrence of malfunctions. In this regard, a photoelectric sensing unit 25 generates a signal BOT indicating the beginning of the tape when there is an absence of a tape at the beginning of the transport 10. Similarly, another photo-optic sensing unit 27 is disposed at the tape 12 between the read head 21 and the take-up reel 23 to sense the absence of the tape 12 thereat, and it generates a signal EOT indicating the end of the tape. An AND gate 29 of the magnetic tape peripheral adapter MPA is enabled in response to both of the signals EOT and BOT being generated to indicate that the tape 12 is broken. A check character timer circuit generates a time-out signal indicating that the longitudinal redundancy check character LRC is overdue. The check character timer

32 is disclosed in greater detail in the foregoing-mentioned patent application Ser. No. 434,742. Similarly, the check characters, both the LRC and the CRC check characters, and the arrangement of the data on the tape 12 are disclosed in greater detail in the foregoing-mentioned patent application Ser. No. 434,742 and articles. Similarly, a vertical parity error detector 34 is provided for sensing the proper code from these CRC check characters and in response to an improper vertical parity generates a signal VERT PAR ERR. A longitudinal parity error detector 36 detects the proper or improper parity of the longitudinal check character LRC and if improper longitudinal parity exists, it generates the signal LONG PAR ERR. For a better understanding of the check characters and the type of parity being monitored, reference may be made to the above-mentioned patent application Ser. No. 434,742 and articles.

A status register 37 of the magnetic tape peripheral adapter MPA includes a series of latches, only pertinent ones of which are shown in FIG. 1. The status register latches are set by the various different error detecting units as hereinafter described in greater detail. A latch BIT 14 of the status register 37 is set by the output of the gate 29 when it is enabled for determining that the tape 12 has become broken or otherwise damaged so that the photo-optic sensing devices 25 and 27 no longer detect the presence of the tape 12.

A latch BIT 19 of the status register 37 is set when the LRC check character has been read by gate circuits (not shown), the circuitry for enabling the latch BIT 19 being disclosed in the foregoing-mentioned patent application Ser. No. 434,742. A latch BIT 20 of the status register 37 is set in response to an AND gate 38, which in turn is enabled by the time-out signal from the check character timer 32 indicating that the LRC character is overdue, the gate 38 being also enabled by the reset output of the latch BIT 19 indicating that the LRC check character has not been received and by the clock signals PH1 and PH2. The time-out signal is generated in response to a count of 21 from the check character timer 32 as more fully described in the above-mentioned patent application Ser. No. 434,742. A BIT 21 latch of the status register 37 is set by a signal VERT PAR ERR from the vertical parity error detector 34, and similarly a BIT 22 latch of the status register 37 is set by a signal LONG PAR ERR of the longitudinal parity error detector 36.

A latch BIT 23 of the status register 37 is a common latch and is set by an OR gate 41 in response to any one of the four latches BIT 14, BIT 20, BIT 21 and BIT 22 indicating that a malfunction has been detected. A set of AND gates 43 when enabled by an instruction signal 200 from an encoder 45 connect the outputs of the status register 37 to a bus 47 to the computer central processor CCP so that it can determine the status of those latches, the encoder 45 being responsive to an instruction received from the computer central processor CCP which in turn formulates and receives those instructions from a program F-74 stored in the computer main memory CMM as hereinafter described in greater detail. The encoder 45 as described in greater in the foregoing-mentioned patent application Ser. No. 434,742 supplies signals for controlling the operation of the magnetic tape peripheral adapter MPA in response to instruction information received from the computer central processor CCP.

Considering now the ticketing device buffer TDB, the device buffer TDB includes a data register and gates therefor generally indicated at 49 for temporarily storing data received from the magnetic tape peripheral adapter MPA and from the computer central processor CCP. The register 49 also serves as a temporary storage area for a scanner peripheral adapter (not shown), which is associated with a scanner (not shown) for monitoring busy connections through the system for generating ticketing information for the computer central processor CCP as more fully described in the foregoing-mentioned patent application Ser. No. 434,742. Thus, the data from the three sources are gated at different times to the register 49. Also, the gates are employed to transfer the data information from the register 49 to the three units—the magnetic tape peripheral adapter MPA, the scanner peripheral adapter SPA and the computer central processor CCP. As more fully and completely described in the above-mentioned patent applications, under normal operation, the scanner peripheral adapter supplies information to the register 49, which in turn transfers the information to the computer central processor. After processing the information, ticketing information is then transferred from the computer central processor CCP to the register 49, which in turn transfers the information to the magnetic tape peripheral adapter MPA for temporary storage in its right register (now shown) as more fully described in the above-mentioned patent application Ser. No. 434,742. The information is transferred from the magnetic tape peripheral adapter right register to the right heads 16 of the magnetic tape electronic unit MTE for transferring the information to tape 12. The magnetic tape electronic unit MTE is also adapted to read information from a tape, for example, during the loading of programs into the computer main memory CMM, and in this regard, the read heads 21 sends the information from tape and transfer it to a read register (now shown) of the magnetic tape peripheral adapter MPA, whereby the information can then be transferred from the read register to the ticketing device buffer register and gate 49.

A status register 52 comprises a series of bi-stable devices in the form of latches, only some of which are shown in FIG. 1.

A latch BIT 0 of the status register 52 is set by a signal LOADING ERR which is generated by circuits (not shown) as more fully described in the foregoing-mentioned patent application Ser. No. 434,742. The setting of the latch BIT 0 indicates that the register and gates 49 is loaded with a word of information and a new data word of information is attempted to be loaded into the register before removing the old data word. A latch BIT 1 is set by the output of a Z field 1-of-N check circuit 54, which is a 1-of-N check circuit for detecting errors in the Z instruction field received from the central processor CCP and decoded by a decoder (not shown) in the ticketing device buffer TDB, the decoded Z field being supplied to the encoder 45 as more fully described in the foregoing-mentioned patent application Ser. No. 434,742. For the purpose of the present invention, it is only necessary to state that the instructions received from the computer central processor CCP are received in the form of an X field, a Y field and a Z field, the X and Z fields being decoded in the ticketing device buffer TDB and the Y field being decoded in the magnetic tape peripheral adapter MPA. A latch BIT 1, a latch BIT 2 of the status register 52 is

set by an output of an X field 1-of-N check circuit 56, which senses errors occurring in the decoded output of the X field. It should be understood that there is a Y field 1-of-N check circuit (not shown) in the magnetic tape peripheral adapter MPA for setting a latch (not shown) of the status register 37, the error detecting units and the status register latches shown in FIG. 1 are represented to illustrate the principles of the present invention.

10 A latch BIT 6 of the status register 52 is set by the output of a data parity error detector circuit 58, which senses parity errors occurring in the register 49. A latch BIT 5 of the status register 52 is enabled by the output of an OR gate 59 which is in turn enabled by the output of an OR gate 59 which is in turn enabled by any one of the other four latches BIT 0, BIT 1, BIT 2 and BIT 6. The gate 59 is also enabled by a signal from the ticketing scanner unit in a similar manner. In this regard, the ticketing scanner unit contains a scanner peripheral adapter which also includes a status register and sensing units which are not described herein since it is only deemed necessary to describe in detail only the status register and error detecting devices of one of the peripheral adapters associated with the ticketing device buffer to illustrate the principles of the present invention.

15 A set of AND gates 61 gate the outputs of the status register 52 to the cable 47 for presentation to the computer central processor CCP. An encoder 63, when it generates its signals, enables the gates 61 in response to an instruction received from the computer central processor CCP via the cable 47.

20 A pair of latches LEZ2 INT and TDB ERROR SENSE LINE of the computer line processors CCP are 30 enabled whenever the latch BIT 5 of the ticketing device buffer status register 52 is enabled for generating signals via AND gates 65 and 67 to the cable 47 for presentation to the computer central processor CCP to serve as an interrupt indicating that an error has occurred. In response to that interrupt signal, the computer central processor CCP responsive to the program module F-74 stored in the computer main memory CMM then isolates the source of the malfunction. In this regard, the computer central processor CCP initially sends an instruction to the encoder 63 to generate

25 the signal for enabling gate 61 to gate the outputs of the status register 52 to the cable 47 for presentation to the computer central processor CCP. As a result, the computer central processor CCP in using the program module F-74 stored in the main memory CMM determines which one of the four error latches is set to thereby discover the source of the malfunction if it occurred in the ticketing device buffer TDB. If none of the latches, other than the main latch BIT 5, of the status register 52 is set, the computer central processor CCP sends an instruction to the encoder 45 to generate the signal 200 for enabling the gate 43, which in turn gate the outputs of the status register 37 to the cable 47 for presentation to the computer central processor CCP. Therefore, the computer central processor CCP can then quickly discover which one of the error latches in the status register 37 is set. As a result, if one of the error latches of the status register 37 is set, the computer central processor CCP thereby quickly ascertains the source of the malfunction. If none of the error latches of the status register 37 is set, then the computer central processor CCP performs diagnostic procedures under software control on both the ticketing device buffer TDB and

the magnetic tape peripheral adapter MPA.

Software Procedure

Referring now to FIGS. 2-1 through 2-11 of the drawings, the software procedure in the form of program module F-74 will now be described. Only FIGS. 2-8 through 2-10 are of particular interest and thus need be described. A source listing based on module F-74 containing explanatory comments for each set of code is included herein as Appendix A. It should be understood that while the program instructions embodied in that listing and the flow chart organization are employed in the preferred form of the present invention, hardware circuits or manually controlled switches may also be employed to control the arrangement of the present invention as will become apparent to those skilled in the art.

As shown in box 201 of the drawings, the module subprogram F74X05 receives control after a ticketing device buffer error interrupt has occurred. The interrupt cause and analysis program (not shown) senses the TDB buffer error interrupt and gives control to F74X05 — the magnetic tape error handler module. As shown in box 202, at this time the system interrupts are disabled. At box 203, computer registers which were not saved by interrupt cause and analysis program are saved by F74X05, which has the first task to determine which TDB buffer is in error (the A unit or the B unit) as shown in boxes 204-207. Index register 3 is set to 0 for unit A or a 1 for unit B. As shown in box 208, an integrity check is made to insure that the unit which signaled the error interrupt was given an assignment to perform. If no assignment was given, a false interrupt was generated, the magnetic tape drive is instructed to stop, all registers in the MPA adapter are reset, all computer processor registers are restored and control is returned to the interrupt cause and analysis program as shown in boxes 247-249, 224-226. The audit timer for timing the return of the TDB interrupt is reset because the TDB error interrupt validly occurred within the prescribed time limit as indicated by box 209.

Referring now to box 210 of the drawings, a check is made to determine whether this error is the result of an attempted retrial of an initial error. If this is the case a fault exists in the subsystem and reconfiguration and diagnostic program must be scheduled. As shown in boxes 211, 251 through 258 and 223 through 226, a check is made to determine if the request write action was a diagnostic request. If it was, then TDB buffer and MPA adapter status directives are obtained and an error code of 3 is returned to the diagnostic program. If the error was on an advance tape an error code of 9 is given to the diagnostic program along with TDB and MPA status.

As shown in boxes 213 and 214, if the request was a non-diagnostic access a check is made to determine whether an advance tape directive was given to the MPA. If not, then the error block count (FMGRBA) is incremented by 1. The MPA and TDB status is obtained and the magnetic tape drive is stopped and all registers and flaps in the TDB and MPA are reset. As

shown in box 227, the job is to be retried and therefore the retry indicator (FMGRTY) is set. As shown in box 228, the ready interrupt switch (FMGRDS) is set to 040000014 in base 8 code. As shown in boxes 229-231, an advance tape command is given to the MPA adapter, the computer registers are restored; the interrupt time out audit is set to insure the response of the MPA adapter; system interrupts are enabled and control is returned to the interrupt cause and analysis program as shown in boxes 224-226.

As shown in box 232, if an error was detected upon the retrial of an initial error a fault is determined to exist in the magnetic tape subsystem. The error block count (FMHRBA) is incremented by 1. As shown in boxes 233-234, the magnetic tape drive is stopped and all registers and flip-flops in the TDB buffer and MPA adapter are reset. After the advance tape (success or failure) the TDB buffer and MPA adapter are reset. As shown in box 235, the TDB buffer and MPA adapter status bits are checked to determine whether a fault exists in the TDB or MPA units.

As shown in boxes 218 and 250, if the adapter MPA was at fault, MPA localization diagnostics are scheduled to run on the faulty unit via the DIACON mechanism Q-register set to 0. As shown in boxes 237-240, a request is made to the configuration control program (CONFIG) to set the faulty MPA adapter in a maintenance out of service (MOS) condition. A check is made to determine whether the MOS request was allowed. As shown in boxes 242-243, if the request was allowed the aforementioned diagnostics (localization) are scheduled on the faulty unit. If the request to CONFIG was not allowed no localization is allowed. As shown in boxes 219-221, an interval is timed for the next program access to the adapter MPA. This is done so that all internal MPA timers are allowed to reset. After the interval a check is made to determine whether any further tasks remain.

As shown in boxes 235-236, if the status bits determine the TDB buffer to be at fault, a check is made to determine whether the TDB buffer is already maintenance out of service. As shown in box 237, if the TDB buffer is not out of service, a request is made to the configuration control program to place the TDB maintenance out of service. As shown in boxes 238-239, if the request is allowed TDB localization is scheduled via diagnostic control to run on the faulty unit. As shown in box 240, if the configuration request was not allowed or if the TDB buffer was already in a maintenance out of service condition, localization is not scheduled upon the TDB buffer. The interval timer is set for allowing MPA timers to recover and when it expires the queues are interrogated for further tasks. Computer registers are restored and control is returned to the interrupt cause and analysis program.

The solution here is the examination of the status bits provided by the ticketing device buffer and the magnetic tape peripheral adapter MPA to determine which unit is at fault and based upon that determination remove the proper unit (TDB or MPA) from service and schedule diagnostic programs to isolate the fault.

What is claimed is:

1. In a communication switching system having a central processor with a main memory therefor and having a peripheral adapter unit for transferring information to and from an input/output peripheral device, a device buffer for transferring information between the peripheral adapter and the main memory, a maintenance arrangement comprising:
  - a plurality of input/output device error detecting units for sensing malfunctions occurring in the input/output peripheral device;
  - a plurality of adapter bi-stable devices associated with peripheral adapter for generating input/output error signals in response to said peripheral device error detecting units sensing malfunctions;
  - a plurality of device buffer error detecting units for sensing malfunctions occurring in the device buffer;
  - a plurality of buffer bi-stable devices associated with the device buffer for generating device buffer error signals in response to said device buffer error detecting units sensing malfunctions occurring in the device buffer;
  - an error bi-stable device responsive to said adapter bi-stable device and to said buffer bi-stable devices generating their error signals for requesting the services of the central processor for maintenance purposes; and
  - control means responsive to said error bi-stable device for monitoring said buffer bi-stable devices to determine whether the malfunction occurred in the

device buffer and for monitoring subsequently said adapter bi-stable devices if the malfunction did not occur in the device buffer to determine the source of the malfunction.

2. A maintenance arrangement according to claim 1, further including buffer gating means for controlling the outputs of said buffer bi-stable devices for determining their status.
3. A maintenance arrangement according to claim 2, wherein said control means activates said buffer gates in response to said error signal.
4. A maintenance arrangement according to claim 3, further including adapter gating means for controlling the outputs of said adapter bi-stable devices for determining their status.
5. A maintenance arrangement according to claim 4, wherein said control means activates said adapter gates after determining that none of said buffer bi-stable devices have been activated by their sensing units.
6. A maintenance arrangement according to claim 5, further including adapter error means for activating said buffer error device in response to any one of said adapter bi-stable devices indicating the occurrence of a malfunction.
7. A maintenance arrangement according to claim 6, further including OR gating means for activating said error bi-stable device in response to said adapter error means or to any one of said buffer bi-stable devices indicating a malfunction.
8. A maintenance arrangement according to claim 7, wherein each one of said bi-stable devices is a latch.
